INTERNAL FRICTION DEVICE

Joseph F. Courtney, Evanston, Ill., assignor to
 International Harvester Company, a corpora-
 tion of New Jersey

Application February 13, 1953, Serial No. 336,722

4 Claims. (Cl. 242—151)

1

This invention relates to a new and improved internal friction device as used in conjunction with uniform strand tensioning and/or uniform driving mechanisms.

The uniform tensioning of strands and/or filaments is extremely important to the overall strength of a fabric made from these strands or filaments. More particularly synthetic fibers such as glass when they are wound on spools normally have irregular stress and strain patterns set up therein thus making it difficult to accomplish the making of a strand or filament having a uniform tensile strength even though the filament is continuous and synthetic.

It is therefore a principal object of the present invention to remove undesirable and unequal stresses and strains from glass or other filaments.

Another important object of this invention is to provide a strand tensioning device which includes the pulling of a glass strand over a roller surface, the rotation of which is controlled by internal friction created within a rubber or elastomer covering of an adjoining roller.

Another important object of this invention is the provision of means in a strand tensioning device for adjustably controlling the rotation of a roller over which a strand to be tensioned is drawn.

Still another important object of this invention is to supply a strand tensioning roller which is snubbed by rolling contact of an adjacent roller.

Another and still further important object of this invention is to provide a strand tensioning apparatus which includes the drawing of a glass or other filament to be tensioned over a roller, the rotation of which is controlled by a rubber covered rotatable member in contact therewith and means regulating the biasing of the rubber covered rotatable member against the strand carrying roller.

Still another important object of this invention is to provide adjustable yieldable contact of a rubber-like covered rotatable snubbing member with a strand carrying roller.

Still another and further important object of this invention is the provision of a friction held lever means for directly biasing a spring for greater or lesser urging of a rubber covered snubbing wheel against a strand carrying roller.

An important object of this invention is to obtain uniform tension on a strand or sheet of material by using the internal friction of a rubber, rubber-like friction wheel or rubber covering of a wheel by compressing the rubber against some member either rotating or stationary.

2

Another object of this invention is to employ an internal frictional resistance to and in any rotational driving mechanism to accomplish a uniform output drive for the particular driving mechanism.

Still another important object of this invention is to supply a rubber or elastomer rotating member which is arranged and constructed to bear against a revolving member, a flat stationary member or a curved stationary member to utilize the internal friction-resisting rotation of the rubber rotatable member to provide for the uniform driving of the mechanism.

The important difference between usual friction devices and the internal friction device of this invention is that in the presently used device there is an external sliding surface subject to comparatively rapid wear and the friction is subject to extreme changes due to surface conditions of the sliding members. With the device of the present invention the friction is a rolling friction and occurs beneath the surface of a rubber member; thus the internal friction of the device of the present invention is more constant and is not subject to extreme changes for any given rubber composition. In the use of the internal friction wheel the replacement of a sliding contact with a rolling contact materially reduces the amount of wear of the contacting surface. It should be understood that the friction wheel employed in this device may take any form and still accomplish the desired result.

Other and further important objects of this invention will become apparent from the disclosures in the following specification and accompanying drawings.

In the drawings:

Fig. 1 is an elevational view partially in section of the strand tensioning device of this invention;

Fig. 2 is a combination sectional and elevational view taken on the line 2—2 of Fig. 1;

Fig. 3 is a top plan view of the device of Figs. 1 and 2;

Fig. 4 is a side elevational view of a modified strand tensioning device of this invention;

Fig. 5 is a sectional view taken on the line 5—5 of Fig. 4, and

Fig. 6 is a sectional view taken on the line 6—6 of Fig. 4.

Fig. 7 is a side elevational view of a modified adaptation of the present invention;

Fig. 8 is an end elevational view, partially in section, of a variable speed driving mechanism having the rolling frictional means of this invention applied thereto;

Fig. 9 is a side elevational view of the device of Fig. 8;

Fig. 10 is a front elevational view of a still further modified form of the invention wherein the internal frictional means of rubber or the like is applied to a planetary gear mechanism, and Fig. 11 is a sectional view taken on the line 11-11 of Fig. 10.

As shown in the drawings:

The reference numeral 10 indicates generally a receptacle for housing a spool or "cake" of continuous glass filament 11. The receptacle 10 is provided with a conical shaped cover 12 which has an opening 13 in the central and apex portion thereof. As shown in Figs. 1 and 2 a strand 14 of the glass spool 11 is shown being pulled outwardly through the opening 13 and thereafter passed through a guide bushing 15 for delivery through the strand tensioning device of this invention. The guide bushing 15 is mounted on a bracket 16 which forms a part of a frame structure 17 which carries the entire strand tensioning device. The term "strand" used herein shall be construed to include rope, single filament, or sheet material.

A roller 18 is journally mounted for rotation on the frame structure 17 and is disposed beneath an upper rotatable member 19 which is similarly journalled for rotation on the frame structure 17. The lower roller 18 is provided with a shaft 20. The shaft 20 is journalled in spaced apart aligned openings 21 and 22 in spaced apart substantially parallel walls 23 and 24 of the frame structure 17. The spaced apart walls 23 and 24 are equipped with upwardly opening spaced apart aligned slots 25 and 26 positioned directly above the spaced apart aligned openings 21 and 22. The upper roll or rotatable member 19 is provided with a shaft 27 and it is the function of the shaft to journally carry the rotatable member 19 within the upwardly opening slots 25 and 26. The rotatable member 19 is provided with an annular rubber covering of substantial thickness in direct engagement with the lower roller 18. The term "rubber" in this specification shall be construed to mean any natural or synthetic rubber or any elastomer or other material capable of resilient deformation. As the glass strand 14 leaves the guide bushing 15 it passes over the lower roller 18, the rotating of which is controlled by the snubbing action of the upper rotatable member 19 thereagainst. The upwardly opening slots 25 and 26 permit the rotatable member 19 to freely ride over the lower roller 18 automatically compensating for irregularities of the circumferential surfaces of the two rollers as well as for various diameter sizes of strands to be tensioned.

The spaced apart walls 23 and 24 of the frame structure 17 have comparable projecting portions 29 and 30 which extend in a direction away from the vertically disposed rollers 18 and 19 and on the opposite side from the guide bushing 15. The projecting portions 29 and 30 include horizontally aligned openings 31 and 32. Arms 33 and 34 are equipped with hinge pins 35 and 36 for their respective journalling in the openings 31 and 32 in the projecting portions 29 and 30 of the frame structure. It should be understood that the arms 33 and 34 are entirely separate and independent of each other and may separately hinge about their hinge pins 35 and 36. The separate arms 33 and 34 project forwardly from their hinge connection to the frame structure over the oposite ends of the shaft 27

of the rubber covered upper rotatable member 19. Thus the arms rest on the shaft 27 causing an urging of the upper rotatable member 19 downwardly against the lower strand carrying roller 18. The variable degrees of rotatable snubbing are accomplished by weights 37 and 38 carried on the arms 33 and 34, respectively. As shown in Figures 1, 2 and 3 weights 37 and 38 are provided with central passages or openings 39 and 40, respectively in order to receive passage of the arms 33 and 34. Each weight 37 and 38 is equipped with a set screw 41 and 42 so that the weights may be simply and easily adjustable along the length of the arms 33 and 34 to obtain greater or lesser biasing of the upper rotatable member 19 against the lower strand carrying roller 18. It should be apparent that when the weights 37 and 38 are positioned at or near the outward ends of the arms 33 and 34, there is a greater load imposed on the rotatable member 19 and it follows that there will be a greater deformation of the rubber covered surface of that rotatable member to the extent that the strand carrying roller 18 is snubbed in its rotation by the internal friction created within the rubber covering of the rotatable member 19 as it bears down against the strand carrying roller 18.

As shown in Figure 1 the glass strand 14 after passing over the roller 18 is carried around the rearward side of the rotatable member 19 and thence forwardly in the direction indicated by the arrow 43. The pulling of the glass strand from its spool 11 in the manner described and as shown in Figures 1, 2 and 3 will tend to uniformly tension the strand and to remove undesirable stresses and strains which are inherently within the strand if they are wound upon a spool or within such a "cake" immediately after formation of the strand by a glass furnace and without other means for eliminating such undesirable stresses and strains. It should be understood that this is not the simple braking of the strand carrying roller 18, but rather is the controlling of the rotation of that roller by the application of a surface deforming rotatable member and the accompanying internal friction of that deformable surface.

A modified form of the invention is shown in Figures 4, 5 and 6. This modified device performs the same strand tensioning function with slightly different apparatus. A glass strand 44 is received from a receptacle (not shown) which would be identical to the receptacle 10 as shown in Figures 1, 2 and 3. The modified tensioning device is provided with a frame support structure 45 which includes a cross arm 46. A roller or sheave 47 is journalled on a shaft 48 which in turn is fixedly mounted on the cross arm 46. The shaft 48 is provided with a bolt head 49 and nut 50 which engages the threaded end of the shaft 48. The sheave or roller 47 is provided with an annular V-shaped groove through and over which the glass or other strand to be tensioned is drawn. It should be understood that the strand carried in the V-groove may extend entirely around the roller or may be wrapped around the roller several times to get the desired capstan effect. At the outer periphery of the strand carrying roller 47 there is an integral annular flange extending laterally therefrom the inner surface of which provides the area for engagement by a rotatable snubber thus making the device comparable to the tensioning device to Figures 1, 2 and 3. A rotatable member 53 corresponding to the rotatable member 19 is

provided with a rubber annular cover 54 of substantial thickness. The rotatable member 53 is adapted to engage the inner annular surface of the lateral extending annular flange 52 of the roller 47 and by reason of the variable degrees of deformation of the rubber covering 54 the rotation of the strand carrying roller 47 is controlled to produce a strand having uniform tensioning.

The rotatable member 53 is journaled on the shaft 55 which is carried on an arm 56 by a threaded attachment thereto as shown at 57. The arm 56 is a part of a bellcrank 58 which is pivotally attached at 59 to the frame structure cross arm 56. The bellcrank 58 is provided with a second arm 60 disposed angularly with respect to the rotatable member carrying arm 56.

An actuating lever 61 which is hingedly attached to the cross frame 46 by means of a bolt 62, a split or other lock type washer 63 is shown in Figure 6 in a position intermediate the bolt 62 and the cross frame 46 to provide for substantial frictional engagement of the actuating lever 61 with the cross frame 46. The operator of the device may adjust the lever arm 61 by pulling it about its hinged bolt 62 causing it to assume different angular relationships with respect to the frame 46, and in view of the friction washer 63 the lever arm tends to maintain the position in which it is manually placed. A coil spring 64 joins the arm 60 of the bellcrank 58 with the actuating lever arm 61 at the location 65 intermediate its hinged attachment with the cross frame 46 and its outer swingable end. When the actuating lever 61 is manually moved in the direction of the arrow 66 the tension on the spring 64 increases causing a greater biasing or urging of the rotatable member 53 against the inner annular surface of over-hanging flange 52 of the strand carrying sheave roller 47. Similarly the manual movement of the actuating lever 61 in the opposite direction will lessen the force of application of the rotatable member 53 against the roller 47 thus minimizing the snubbing of the strand carrying roller 47 by the rotatable member 53. The rotatable members 49 and 53 perform identical functions in the two forms of this invention as shown in Figures 1 and 4. In the modified form of the tensioning device the glass strand 44 is pulled upwardly as indicated by the arrow 67 and is carried over and around the strand carrying sheave 47 which similarly rotates in the same direction as indicated by the arrow 68.

As in the strand tensioning device in Figures 1 to 3 the strand tensioning device of Figures 4 to 6 functions to control the rotation of the strand carrying roller by the surface deformation of a snubbing rotatable member. In both instances there are means provided for adjusting the degree of force by which the rotatable member contacts the strand carrying roller and thus simultaneously causing surface deformation of the rotatable member and the creating of an internal friction within the deformable surface to snub the strand carrying roller which has a substantially non-deformable surface. The running of a strand through this device thus gives the strand a uniform tensioning. Such uniform strand tensioning is the result desired and after such a strand has been so rid of its undesirable irregular stresses and strains it is suitable for many applications such as fabrics and/or twines with the expectation that the resulting fabric and/or twines may be of a uniform strength throughout their entireties.

As shown in Fig. 7, the reference numeral 70 is

directed to a stationary supporting structure upon which is journally mounted a winding spindle or the like, 71. The spindle is adapted to receive a tube, bobbin, cone or the like, such as shown at 72, upon which is wound a strand of material shown at 73. A device commonly termed a "builder mechanism" 74 is adapted to press against the surface of the package of strand material being wound onto the member 72. The builder mechanisms in the past have performed various functions such as constituting size-limiting means for rolls of material and causing the strand of material to lay in an even and uniform manner on a spool or the like. The builder mechanism as shown in Fig. 7 includes a pad 75 which engages the surface of the material wound on the spool 72. The pad 75 is carried on an arm 76 which is pivotally mounted at 77 on the stationary supporting structure 70. The lower end of the arm 76 terminates in a fork 78 for journally carrying a wheel member 79 on a shaft 80 spanning the fork 78. The wheel member 79 includes a core or hub portion 81 and a rubber or elastomer peripheral covering 82. An arcuate stationary surface is provided at 83 forming a track on which the wheel member 79 may travel. The arcuate member 83 forms a part of a circle with its center being the axial center of the hinge 77 of the arm 76. Further, the track member 83 forms a part of the stationary supporting structure 70. The radius of the track member 83 is slightly less than the radius of the builder mechanism arm 76 from the hinge 77 to the outer extremity of the rubber periphery 82 of the wheel 79. It will thus be seen that the rubber peripheral surface 82 of the wheel 79 will be somewhat compressed at the point of rolling contact with the stationary curved track 83. It will thus be seen that the builder mechanism as employed in this Fig. 7 performs the added function of determining the density or compactness of the package being formed. The arcuate movement of the builder mechanism, as the package increases in diameter, is limited by reason of the internal friction occasioned within the annular rubber covering 82 of the wheel member 70 as that wheel is urged against the stationary curved surface 83 and thus the weight of the package being formed may be closely controlled. Rotation of the friction wheel 79 requires a certain amount of work with a given pressure of the friction against the stationary surface and it is thus evident that the package weight may be controlled for a definite diameter of package.

Figs. 8 and 9 show the application of internal friction to a variable speed driving mechanism. The mechanism includes a pair of spaced-apart, axially aligned shafts 84 and 85, each of which is equipped with a beveled pinion gear 86 and 87. The beveled pinions 86 and 87 mesh with opposed beveled pinion gears 88 and 89 which are carried within a ring member 90. Rotational drive is delivered to the shaft 84 by reason of the braking of rotation of the ring member 90, rotational drive is thus transmitted to the output shaft 85. A rotatable wheel member 91 having a hub or core 92 and an outer annular rubber or elastomer covering 93 is carried on a shaft 94 which is mounted on and across a forked portion 95 of an arm 96. As best shown in Fig. 9 the arm 96 is pivotally mounted at 97 on a stationary supporting structure 98. The far end of the arm 96 is shaped in the form of a handle 99 so that the arm and its associated wheel 91 may be arcuately swung about the hinge 96 for more or less engagement with the ring member 90 of the variable speed driving

mechanism. An arcuate rack member 100 is formed on the stationary supporting structure 98 and is adapted to be engaged by a pawl or latch member 101 which is hingedly mounted on the arm 96 at 102. Thus, after manual adjustment of the arm 96 has been made the pawl is put into the notch lying adjacent thereto on the rack 100. It is therefore evident that after adjustment is completed the arm 96 remains in fixed position with the rubber covered wheel 91 in a fixed degree of compressing engagement with the differential ring member 90. Here, again, the primary principle is to substitute a rolling internal friction for the usual external sliding friction. Rotation of the ring member 90 is thus accurately controlled through the internal friction developed within the annular rubber member 93. In this modification, as shown in Figs. 8 and 9, it is not necessary that the drive mechanism be solely for a strand or sheet material. The end result in a driving mechanism employing this internal rolling friction as a means for snubbing the drive is a uniform and completely controlled output.

In addition to adapting the internal frictional snubbing device of this invention to a differential means, the modification, as shown in Figs. 10 and 11, provides for the adaptation of the invention to a planetary gear drive mechanism. An input drive shaft is shown at 103 and has a carrier 104 fixedly attached thereto so that as the shaft 103 rotates, so will the carrier 104. The carrier 104 has journally mounted thereon spaced-apart planet gears 105 and 106 which are disposed between an outer ring member 107 having an internal annular ring 108 and a centrally disposed sun gear 109. The sun gear 109 is mounted on and is fastened to a shaft 110 which is spaced apart but in axial alignment with the input shaft 103. The shaft 110 constitutes the output drive shaft of this driving mechanism. The ring member 107 has a disk-like supporting structure 111 which is carried on a bearing member 112 disposed about the output drive shaft 110. The outer annular surface of the ring member 107 is engaged about a rolling wheel member 113, as shown in Fig. 10, which is quite similar in construction to the wheel member 91, as shown in Figs. 8 and 9. The wheel 113 includes a hub 114 and an outer annular rubber covering 115 which provides the means for obtaining the internal frictional resistance to the drive delivered to the output shaft 110. The wheel 113 is mounted on a bellcrank arm 116 which is pivotally carried at 117 on a supporting structure 118. A weight 119 is slidably mounted on the ram arm of the bellcrank 116 and is adjusted in any desired position therealong by an adjacent set screw 120. The greater the distance the weight 119 is located from the pivotal mounting 117, the greater will be the urging of the wheel 113 against the ring member 107, and thus the resultant drive of the output shaft 110 will be increased. An absence of snubbing of the ring member 107 in the device as shown in Figs. 10 and 11 would result in no drive being delivered to the output shaft 110. Any rotational drive mechanism delivered to the device through the input shaft 103 would be dissipated in the mechanism by the free running of the planet gears and ring gear and there would be no effective drive to the output sun gear 109. In the same manner that the differential drive is caused to have a uniform output, so also is the planetary drive output made uniform by the snubbing of the ring member 107 by means of the internal friction within the rubber or elastomer covering 115.

Numerous details of construction may be varied throughout a wide range without departing from the principles disclosed herein, and I therefore do not propose limiting the patent granted hereon otherwise than as necessitated by the appended claims.

What is claimed is:

1. In a strand tensioning device, a support, a first roller journalled thereon and providing a peripheral strand engaging surface, means for controlling rotation of the roller, said means comprising a second rotatable member having a shaft extending laterally outwardly from both ends, said support having spaced apart upwardly open slots located above said first roller for receiving the shaft of the second rotatable member whereby said second rotatable member may have movement toward and away from said first roller, a peripheral deformable annular surface on said second rotatable member engaging the roller, separate means urging each end of said shaft downwardly into the bottoms of the upwardly open slots, said separate means including spaced apart separate arms hingedly mounted on said support adjacent said upwardly opening slots, and individual weight means adjustably carried on each of said arms, said arms engaging the shaft extensions of said second rotatable member and urging it into contact with said first roller.
2. In a strand tensioning device, a support, a sheave journalled thereon, said sheave having an annular flange adjacent the outer periphery thereof, means for controlling rotation of said sheave, said means comprising a rotatable member, said rotatable member having a peripheral deformable outer annular surface arranged and constructed to engage the inner surface of the annular flange of the sheave, a bellcrank lever hingedly mounted on said support, said bellcrank lever having angularly spaced apart arms, said rotatable member journally mounted on one of the arms of said bellcrank lever, and spring means engaging the other arm of said bellcrank lever to urge said rotatable member into surface deforming engagement with the inner surface of said annular flange.
3. A device as set forth in claim 2 in which a lever arm is hingedly mounted on said support in spaced apart position with respect to the hinging of said bellcrank lever, and said spring means joining said lever arm, whereby angular changes of said lever arm directly control the spring means for greater or lesser urging of said rotatable member against the annular flange of the sheave.
4. A builder mechanism for a strand winder comprising a stationary supporting structure, a spindle on said supporting structure, a tube on said spindle, a strand wound on said tube, a strand-engaging pad, an arm hingedly mounted intermediate its ends on said supporting structure, one end of said arm carrying said pad, the other end of said arm journally carrying a wheel, said wheel having an annular rubber outer periphery, a curved surface carried by said supporting structure and generated about the arm hinge as a center, the radial distance between the arm hinge and the curved surface being somewhat less than the length of the arm between its hinge and the outer rubber annular periphery of the wheel whereby the rubber periphery is compressed and rolling of the wheel on the curved surface by the building of strand on the tube is resisted by internal friction within the rubber periphery.
